(Cl. D80—10)

To all whom it may concern:

Be it known that I, Sherman J. Sexton, a citizen of the United States, residing at Chicago, in the county of Cook and State of Illinois, have invented a new, original, and ornamental Design for a Revolving Holder for Bottles and Other Containers, of which the following is a specification, reference being had to the accompanying drawings, forming part thereof.

Figure 1 is an elevational view of a revolving holder for bottles and other containers embodying this invention.

Figure 2 is a plan view of the same.

Figure 3 is a perspective view of the same.

I claim:

The ornamental design for a revolving holder

for bottles and other containers, substantially as shown.

SHERMAN J. SEXTON.
